UNITED STATES PATENT OFFICE.

WILLIAM TAZEWILL BURROUGHS, OF BLUEFIELD, WEST VIRGINIA, AS
SIGNOR OF ONE-HALF TO HENRY M. NASH, OF SAME PLACE.

CHURN.

SPECIFICATION forming part of Letters Patent No. 615,676, dated December 13, 1898.

Application filed October 9, 1897. Serial No. 654,699. (No model.)

To all whom it may concern:

Be it known that I, WILLIAM TAZEWILL BURROUGHS, a citizen of the United States, residing at Bluefield, in the county of Mercer 5 and State of West Virginia, have invented a new and useful Churn, of which the following is a specification.

My invention relates to churning; and the objects and advantages of the same will appear 10 in the following description, and the novel features thereof will be particularly pointed out in the appended claims.

In the drawings, Figure 1 is a side view of a churn mechanism constructed in accordance 15 with my invention. Fig. 2 is a plan view of the same. Fig. 3 is a transverse vertical section of the operating mechanism on the line 3 3 of Fig. 2. Fig. 4 is a perspective view of the receptacle-holding and dasher-stem-guiding devices. Fig. 5 is a detail horizontal section to show the guiding devices for the dasher-stems and the means whereby the 20 churn-receptacle lid is removable without disconnecting the dasher-stems. Fig. 6 is a detail 25 tail sectional view to show the manner of mounting the lid upon the receptacle. Fig. 7 is a detail section to show the swiveled bearing for the intermediate or counter shaft.

Similar numerals of reference indicate corresponding parts in all the figures of the drawings.

Rising from a base 1 are standards 2, connected by suitable horizontal braces 3 to form a supporting-frame, and mounted transversely 35 in suitable bearings supported by said frame is a driving or drum shaft 4, provided with independent drums 5 and 6, upon which are reeled weight-cords or connections 7. These weight-cords extend over elevated guides 40 consisting of pulleys 8, supported by derricks or uprights 9, rising from the supporting-frame, and the weights 10 are provided at their lower ends with hooks 11 and at their upper ends with eyes 12 to provide for employing 45 a series of weights for suspension by each cord. This enables the operator to vary the weights to suit the work to be accomplished. The drum or driving shaft may be provided with any suitable means whereby it 50 may be rotated to wind the weight-cords; but

I prefer to fit it at one end with a key-seat 13, adapted to receive a crank, (not shown,) and it is also desirable to fit said shaft with a ratchet mechanism 14, whereby it may be held from backward rotation during the winding of said weight-cords, this ratchet mechanism to be thrown out of gear by disengaging the pawl thereof from the ratchet-wheel when it is desired to operate the mechanism. 55

The driving-shaft carries a driving-gear 4^a, 60 by which through intermediate gearing motion is communicated to a crank or driven shaft 15, also mounted in suitable bearings upon the frame and provided with terminal crank-arms 16, connected by pitmen 17 with 65 dasher-stems 18. The body portion of the crank-shaft is cross-sectionally squared or otherwise constructed to provide for the removal and replacement of a pinion 19 and a balance-wheel 20 without allowing relative 70 independent rotation of said parts, and the terminal cranks of said shaft are reduced toward their free ends to provide for taking said pinion and balance-wheel on and off over the crank-arms, which are preferably constructed integral with the shaft. The pitmen are connected with the crank-arms by means of suitable wrist-pins 21 on the latter and are bifurcated at their lower ends to receive the contiguous extremities of the dasher- 75 stems, split keys 22 being engaged with registering openings in the pitmen and dasher-stems to provide for the disconnection of said parts with facility. 80

The preferred construction of means for 85 communicating motion from the driving-gear on the driving-shaft to the pinion on the driven shaft includes an intermediate or counter shaft 23, provided with a pinion 24 for meshing with said driving-gear and a gear 90 25 of larger diameter for meshing with the pinion on the driven shaft. This intermediate or counter shaft is mounted in bearings on the frame, one of those bearings, 26, being swiveled, while the other, 27, is movable toward and from the driving-shaft to provide for throwing the pinion 24 into and out of operative relation with the driving-gear 4^a. Said movable bearing 27 is carried by a slide 95 28, mounted in a suitable guide 29 on the 100

supporting-frame and connected with a shift-lever 30, which is fulcrumed at 31 upon the supporting-frame. In this connection I also employ a brake-bar 32, mounted in a suitable guide 33 and provided with a toothed extremity to engage the teeth of the driving-gear 4^a and lock the mechanism against rotation when it is desired to check the operation of the machine with the actuating-weights 5 in an elevated or operative position. Said brake-bar is connected with an operating-lever 34, fulcrumed upon the framework.

The churn-receptacle 35 is fitted in a seat on the base 1, said seat consisting of a plurality of fixed blocks 36 and a movable block 37, pivoted, as at 38, to the base and provided at its free end with a locking device consisting of a hook 39 or its equivalent for engaging an eye 40. It is obvious that when this 15 movable seat-block is locked in place the churn-receptacle is held at its bottom against movement, and in order to remove the receptacle it is necessary to displace said movable block, as indicated by dotted lines in Fig. 4. 20

25 The churn-receptacle is provided with a removable lid or cover 41, provided on its under surface with strips 42 to fit within the top of the receptacle and also provided with guide-openings 43, through which the dasher-stems 18 extend. In order to allow the receptacle lid or cover to be removed from the receptacle without disconnecting the dasher-stems from the pitmen, I provide said lid or cover with movable sections 44, pivotally 30 mounted at one end by hinge-straps 45 or their equivalents upon the main section of the lid or cover and extending inwardly to the guide-openings 43, whereby when said movable sections are swung laterally to occupy a position indicated in dotted lines in Fig. 5 said guide-openings are opened to one edge of the lid. When the churn is in operation, it is necessary to hold the lid of the receptacle firmly in place, and to accomplish 40 this I employ holding-bars 46, pivotally mounted, as at 47, upon the frame and provided in their under sides with rabbets 48, which engage the edges of the lid or cover. The free ends of these holding-bars are held 45 in their depressed or operative positions by means of a bail-lock 49, having its arms pivotally mounted upon the standards of the frame and adapted to swing over said free ends of the holding-bars when the latter are 50 engaged with the churn lid or cover. This lock is provided with an operating knob or handle 50 to facilitate its disengagement from the holding-bars. In connection with the holding-bars I also preferably employ a 55 dasher-stem guide 51, arranged transversely of the frame and terminally supported by brackets 52 on said holding-bars, and this guide-bar is provided with dasher-stem guide-openings 53, closed by swinging blocks 54, hinged or otherwise movably mounted at 55 upon the body of the bar and adapted to be secured in position at their free ends by a

common locking device consisting of a button 56, which is pivotally mounted upon the body portion of the bar. When it is desired 70 to raise the holding-bars to release the churn-receptacle without disengaging the dasher-stems from the pitmen, this locking device 56 should be turned to disengage it from the closing-blocks 54, after which the holding-bars, previously released by the bail 49, may be elevated to disengage the rabbets 48 from the churn lid or cover. It will also be seen that the dasher-stems may be disengaged from the pitmen to provide for the removal of the 80 dashers, with the churn-receptacle, from the supporting-frame, the closing-blocks 54 first being released and the bail-lock 49 being elevated to disengage the holding-bars.

In practice I prefer to employ a churn of 85 medium depth and provide perforated plungers 57, which while having only a small throw are adapted to thoroughly agitate the contents of the receptacle, and thus hasten the operation of churning.

Various changes in the form, proportion, and the minor details of construction may be resorted to without departing from the spirit or sacrificing any of the advantages of this invention.

Having described my invention, what I claim is—

1. The combination with a supporting-frame, and a churn-receptacle seated upon the base of the frame, of a receptacle lid or cover having guide-openings for dasher-stems and provided with swinging sections movable in the plane of the lid or cover, whereby said guide-openings are normally closed, pivotal holding-bars mounted upon the supporting-frame for vertical swinging movement and provided with rabbets for engaging opposite side edges of said receptacle lid or cover in the paths of the swinging sections thereof, and means for securing said holding-bars in their normal positions, substantially as specified.

2. The combination with a supporting-frame, and a churn-receptacle seated upon the base-frame, of holding-bars pivotally mounted upon the frame for vertical swinging movement, a guide-bar supported by said holding-bars at intermediate points and provided with dasher-stem guide-openings fitted with closing-blocks, means for securing the closing-blocks in their normal positions, a receptacle lid or cover removably fitted upon the receptacle in the paths of said holding-bars for engagement thereby, and means for securing the holding-bars in their normal positions in engagement with opposite edges of the lid or cover, substantially as specified.

3. The combination with a supporting-frame, and a receptacle seated upon the base of said frame, of holding-bars pivotally mounted upon the frame for vertical swinging movement, and adapted to bear upon the receptacle lid or cover, a guide-bar carried by the holding-bars at intermediate points and provided with dasher-stem guide-openings fitted

with movable closing-blocks pivoted to the bar at their remote ends, a common locking-button 56 for engaging the adjacent ends of and securing said closing-blocks in their normal positions, and means for securing the holding-bars in their normal positions in engagement with the receptacle lid or cover, substantially as specified.

4. The combination with a supporting-frame, dasher-operating mechanism including a driving-shaft and pitmen actuated thereby, and a churn-receptacle seated upon the base of the supporting-frame, of a receptacle lid or cover removably fitted upon the receptacle and provided with dasher-stem guide-openings and pivotal closing-blocks for said openings, said closing-blocks being mounted to swing laterally in the plane of the lid or cover, dasher-stems extending through said guide-openings and detachably connected with the pitmen, pivotal holding-bars mount-

ed upon the supporting-frame for vertical swinging movement and rabbeted to engage the side edges of said receptacle lid or cover and closing-blocks, a guide-bar carried by and spanning the interval between the holding-bars and provided with dasher-stem guide-openings and movable closing-blocks for said openings, means for securing said guide-bar closing-blocks in their operative positions, 30 and a swinging bail mounted upon the supporting-frame to normally occupy a position in the paths of the free ends of the holding-bars to prevent swinging movement thereof, substantially as specified.

In testimony that I claim the foregoing as my own I have hereto affixed my signature in the presence of two witnesses.

WILLIAM TAZEWILL BURROUGHS.
